UNITED STATES PATENT OFFICE.

JOSEPH O. BEAZLEY, OF BALTIMORE, MARYLAND.

FEED-TROUGH FOR POULTRY-COOPS.

SPECIFICATION forming part of Letters Patent No. 341,211, dated May 4, 1886.

Application filed November 14, 1885. Serial No. 182,887. (No model.)

To all whom it may concern:

Be it known that I, JOSEPH O. BEAZLEY, a citizen of the United States, residing at Baltimore, in the State of Maryland, have invented 5 new and useful Improvements in Feed-Troughs for Poultry-Coops, of which the following is a specification, reference being had to the accompanying drawings.

This invention relates to improvements in 10 feed-troughs for poultry-coops used for transporting all kinds of fowls to a distant market; and the object of the improvements is to furnish water and feed for them, so that they can drink and feed during their transit, thereby 15 keeping them in good condition, and also to provide a construction which will prevent the waste of food and water, all of which will be hereinafter more fully described, and pointed out in the claims.

20 In the accompanying drawings, forming a part of this specification, Figure I is a longitudinal vertical section of an ordinary wire coop having the improvements attached. Fig. II is a vertical section of Fig. I on line *x* 25 *x*. Fig. III is a plan view of the feed-trough and water-bottles. Fig. IV is a vertical section of Fig. I on line *y* *y*. Fig. V is a vertical section of the water-bottle and elevation of the feed-trough enlarged. Fig. VI is a vertical 30 section of Fig. V on line *z* *z*.

A represents an ordinary wire coop or basket, as represented in Fig. I. Next to one of the sides within the coop, some distance from the top, to permit the fowls to reach the 35 water and food, the bottles B B', with the food-troughs C C' attached, are secured by wires in such a manner as to prevent them from being accidentally detached. The troughs C and C' are constructed as shown in Figs. V and 40 VI, having vertical sides and a bottom slightly dished to the middle, and the top opening flared downwardly to a narrow slit, *c*, which troughs are permanently fastened to their respective bottles B B' at one end, the 45 other end of each trough being open. One of the troughs, C, is a little larger, to permit the smaller one, C', to slide within it.

The bottles and troughs can be made of tin or other sheet metal, according to the sections 50 shown in the several figures, having the coni-

cal or flared entrance *b*, with circular orifice *b'* in the bottles B B', and elongated slit or opening *c* *c'* of the troughs C C', for the bills of the fowls to enter, and yet not being large enough to admit the head.

The object of having one of the troughs to slide within the other is, that when thus closed they can be easily passed through the door of the coop, and then they can be elongated until the two bottles are placed in 60 the corners of the coop, where they are to be secured by wires or other effectual devices, and similar wires are to be passed around the ends and secured to the side of the coop. The troughs and bottles can by a 65 reverse process be removed for cleansing.

It is well known to all parties engaged in shipment of poultry as heretofore practiced that no secure and proper means have been adapted to water fowls when "in transit," 70 hence they are invariably in a distressed condition upon arrival at a market, and also in regard to the food furnished them. By dropping it into the basket a large quantity is wasted. By these improvements the fowls 75 have a secure and bountiful supply of food and water, and no turning over of the coop, should such an accident occur, can occasion a loss of either food or water, owing to the well-known efficacy of the form of the wa- 80 ter-bottle and trough, which form is not claimed by me, nor supplying food to fowls in transit; but

What I do claim is—

1. In combination with a poultry-coop, the 85 herein-described telescopic feed-troughs, each having an open top with downwardly-flared extensions throughout its length.

2. In coops for transportation of poultry, food-troughs C and C', constructed to slide 90 one within the other, and having at one end of each, attached thereto, a water-bottle, substantially as and for the purpose described.

In testimony that I claim the foregoing as my own I hereto affix my signature in presence of two witnesses.

JOSEPH O. BEAZLEY.
